STOKER APPARATUS

Robert A. Foresman, Prospect Park, Donald J. Mosshart, Ardmore, and Arthur F. Schultz, Springfield, Pa., assignors to Westinghouse Electric & Manufacturing Company, East Pittsburgh, Pa., a corporation of Pennsylvania

Application December 31, 1940, Serial No. 372,640

17 Claims. (Cl. 110—44)

This invention relates to stokers, more particularly to progressive feed stokers and means for disposing of the ash from the discharge ends of such stokers, and it has for an object to improve the efficiency of this type of apparatus.

Another object of the invention is the provision of an extension grate construction for use with progressive feed stokers, which construction has improved agitating and pushing action.

These and other objects are effected by the invention as will be apparent from the following description and claims taken in connection with the accompanying drawings, forming a part of this application, in which:

Fig. 1 is a perspective view of a progressive feed stoker embodying the improved extension grate construction;

Fig. 2 is a longitudinal sectional view through a furnace containing a stoker such as shown in Fig. 1;

Fig. 3 is a plan view of the extension grate construction with the moving bars thereof in retracted forward position;

Fig. 4 is a view similar to Fig. 3 but with the moving bars in their extended rearward position;

Fig. 5 is a transverse sectional view taken along the line V—V of Fig. 3, looking in the direction of the arrows;

Fig. 6 is a view similar to Fig. 5, but with the moving bars in a different position;

Fig. 7 is a transverse sectional view of one of the moving grate bars, the view being taken along the line VII—VII of Fig. 6;

Fig. 8 is a fragmentary view similar to Fig. 7, but showing a grate bar with the central portion omitted;

Fig. 9 is a side elevational view of a modified type of stationary grate bar; and,

Fig. 10 is a transverse sectional view taken along the line X—X of Fig. 9, looking in the direction of the arrows.

An extension grate construction for use with a progressive feed stoker has two main functions: the first being to break up and agitate the bed of burning fuel passing thereover to permit uniform flow of air through the same for promoting combustion, and the second being to positively eject the ash and non-combustible refuse as it reaches the discharge end of the extension grate.

In view of these functions, the extension grate may be considered to comprise first and second zones of action, considered in the direction of fuel feed. In the first zone, which extends from the discharge end of the underfeed section to a

point near the discharge end of the extension grate, the fuel fed thereto should be completely consumed, hence the grate action in this zone should be primarily that of agitation to break up any clinker formations and to provide for ample penetration of air to the fuel bed to insure complete combustion of the fuel prior to its leaving this zone.

If the extension grate properly performs the above functions in its first zone, the second zone, which extends from the discharge end of the first zone to the ash pit, will receive only ash and non-combustible refuse. This being the case, the grate action in the second zone should be primarily that of pushing to eject the ash and refuse.

Therefore, the present invention provides, for use at the discharge end of a progressive feed stoker, an extension grate construction comprising a first transversely-extending row of grate bars, a number of said bars being adapted to reciprocate and being interspersed among the remaining bars, which are stationary. This first row of bars provides a first zone in which the main action applied to the fuel bed is that of agitation, although, of course, definite feeding action is also present. Following this first row of grate bars is a second transverse row of bars, all of which are adapted to reciprocate and are provided with rearwardly-facing fuel-contacting and pushing surfaces, which surfaces are inclined sufficiently to insure positive ejection of the ash and refuse fed thereto from the first row of grate bars constituting the first zone.

The construction includes a single reciprocatory member for imparting reciprocation to all of the reciprocating grate bars, and an angularly adjustable support for the rearward ends of the grate bars of the last row, whereby the pushing effect of these bars may be varied in accordance with the angular adjustment of the supporting member therefor.

Referring now to the drawings more in detail, and with particular reference to Figs. 1 and 2, the reference numeral 10 indicates a furnace in its entirety. The furnace comprises a front wall 11, side walls 12 and a rear or bridge wall 13. The furnace walls define a combustion chamber 14 within the lower portion of which is disposed a stoker 15 comprising an underfeed section 16 of alternately arranged retorts 17 and tuyère rows 18, the stoker having an overfeed section 19 which comprises the subject-matter of the present invention. An air chamber 20 is pro-

vided beneath the stoker and serves to supply air for supporting combustion.

In operation, fuel is fed from a hopper 21 into the ends of the retorts 17 by means of primary rams 22 reciprocating within a ram box 23, and the fuel is advanced along the retorts and forced upwardly over and onto the tuyère rows 18 by means of secondary rams 24 reciprocating within the retorts. As the fuel moves over the discharge end of the underfeed section, it is received by the 10 overfeed section and, due to the action of the latter, is thoroughly agitated and positively pushed thereover toward the final point of discharge.

The overfeed or extension grate construction comprises a plurality of transversely-extending rows of grate bars, two rows, 26 and 27, being herein illustrated. The row 26 comprises a number of reciprocating grate bars 28 interspersed among a number of stationary bars 29. The second row comprises a plurality of reciprocating bars 30.

A cross-head 32, adapted to reciprocate in a direction longitudinally of the stoker, extends transversely of the extension grate construction and is supported for sliding movement upon a bearing plate 33 carried by the frame structure 34, 35, and 36. Means for imparting reciprocating motion to the cross-head 32 is provided and comprises a plurality of rods 37 connected at one end to the cross-head and at the other end, at 38, to double crank arms 39 fixedly secured on the transversely-extending shaft 40, which is mounted for limited oscillatory movement in the bearing member 41. This bearing member may be bolted, as at 42, or otherwise secured, to the stoker frame 43.

Suitable means are provided for imparting limited oscillatory movement to the shaft 40, which means comprises the lower portion of the double crank arm 39, the rod 45 and the adjustable link 46 and rod 47 having adjustable connection through the eccentric 48 with the stoker engine 50.

In order that reciprocation of the cross-head 32 may impart corresponding motion to the reciprocating first grate bars 28, the latter are provided on the under faces of their rearward ends with depending lugs 51 adapted to be received in mating recesses 52 in the upper surface of the cross-head. For manufacturing reasons, it may be desirable to form these recesses 52 as slots open at the forward edge of the cross-head and to close the same by a transversely-extending plate 53 bolted, or otherwise secured, to the cross-head (Fig. 1). The forward ends of the reciprocating first bars 28 rest upon rockers 54, which are supported through arms 55 upon the transversely-extending shaft 40 carrying the double crank arms 39. The bearing surfaces of the rockers 54 and the length of the arms 55 are so designed and proportioned that there is substantially pure rolling action between the rockers 54 and the forward ends of the reciprocating bars 28 resting thereon, whereby substantially all sliding friction between the upper ends of said bars and their supports is eliminated.

The stationary bars 29 of the first row 28 are individually supported by laterally-spaced brackets 57, bolted or otherwise secured to the stoker frame structure. Each bracket has an upwardly-extending lug 58 adapted to be received in a downwardly-opening recess in the lower face of the forward end of each of the stationary bars 29.

The brackets 57 and their lugs 58 are spaced

apart laterally a distance equal to or greater than the width of the forward ends of the reciprocating bars 28, normally disposed therebetween. It will be apparent that, in order to remove any reciprocating bar 28, it is only necessary to lift the rearward end thereof a sufficient distance to remove the lugs 51 from their recesses 52, whereupon the bar may be moved rearwardly to withdraw the forward end thereof from between the adjacent brackets 57.

It will be noted that the discharge end of the progressive feed stoker has a rearwardly-projecting lip structure 60 overhanging the forward ends of all of the grate bars 28 and 29 of the first row 26. This overhanging structure 60 is disposed so close to the forward ends of the grate bars which it overlies that there is not sufficient space to raise the upper ends of the stationary bars enough to separate the upwardly-projecting lugs 58 from their mating recesses 59. However, any selected stationary grate bar may be removed, simply by removing a reciprocating bar adjacent thereto and then sliding a stationary bar laterally into the space previously occupied by the reciprocating bar, whereupon the stationary bar may be slid rearwardly until its forward end is clear of the overhanging structure 60. The rearward ends of the stationary bars 29 merely rest upon the cross-head 32, which slides or reciprocates therebeneath.

In the second or last row 27, the grate members 30 are pivotally supported at their forward ends by brackets 61 formed integral with, or permanently attached to, the cross-head 32. Each bracket 61 has a pair of upwardly-extending lugs or flanges 62 having aligned transversely-extending openings 63 therethrough, adapted to receive suitable means, such as pivot pins (not shown), for pivotally supporting and securing the forward ends of the bars 30 thereto.

The rearward ends of the bars 30 are supported by, and adapted to slide upon, an ash-supporting structure 65. This ash-supporting structure comprises a base plate 66 pivotally mounted, as at 67, on a bracket 68 secured to the frame member 34. A link 69 is pivotally connected to an arm 70 by pin or bar means 71; the arm 70 being clamped or fixedly secured to a shaft 72 extending transversely of the furnace and preferably having one end thereof extending through the furnace side wall, whereby it may be given a limited rotary movement from without the furnace by an operator. It will be apparent that the ash-supporting structure 65 may be angularly adjusted about the axis at 67 by limited partial rotation of the operating shaft 72. The ash-supporting structure has two bearing surfaces for the grate bars 30, one surface being at 73 on the base plate 66, and the other being provided by a sectional ash-supporting member 74 having an upper surface 75. Reference to Figs. 5 and 6 will indicate that when the ash-supporting member 74 is in a substantially horizontal position adjacent the upper limit of its adjustment, the last grate members 30 will bear upon the surface 75, while when the ash-supporting structure is lowered, as illustrated in dotted lines in Fig. 5, the bars 30 will bear upon the surface 73. Obviously, there is an intermediate position of the ash-supporting structure at which the bars 30 will bear in part upon the surface 73 and in part upon the surface 74, depending upon which portion of their reciprocating stroke or length of travel they are going through.

Referring to Figs. 2, 5 and 6, it will be seen

that the furnace rear or bridge wall 13 has a curved portion 77 disposed in overlying relation to the ash-support member 74. The curved portion 77 and the ash-supporting member 74 define therebetween a transversely-extending, longitudinally-converging ash discharge outlet 78. As indicated by the dot and dash line shown in Fig. 5, this converging passage 78 may be adjusted so that it is converging or converging-diverging, depending upon the angular adjustment of the ash-supporting member. Preferably, the portion 77 of the rear wall 13 which overlies or is in close proximity to the ash discharge outlet 78 is water cooled, as by means of tubes 79. In some cases it may be desirable to provide the curved portion 77 of the furnace rear wall with a depending lip or nose block 80 to catch, or retard the discharge of, unconsumed fuel which would otherwise pass through the discharge opening 78 to the ash pit.

Referring to Figs. 7, 8, 9, and 10, there is provided a novel composite construction of grate members 28 and 29, the construction shown in Fig. 7 being that of a reciprocatory grate bar 28. The bar is made up of side sections A and C and an intermediate section B, these sections being held together by a plurality of bolts 81 extending through abutting bosses 82 and 83 carried by the sections B, and A and C, respectively. Preferably, the members A, B and C are provided, on their adjacent faces, with a plurality of pins or knobs 84 and a plurality of beads or ribs 85. The members A and C are provided on their outer sides with horizontally-disposed ribs 86, and, as indicated in Figs. 3 and 4, these ribs on adjacent reciprocatory and stationary bars overlap, the ribs on the stationary bars being at different heights than those on the adjacent reciprocatory bars. In order that the reciprocatory bars may be removed in the manner previously explained, that is, by lifting the rearward ends sufficiently to remove the depending lugs 51 from their mating recesses 52 and then moving the bars rearwardly, the ribs 86 are so arranged that there will be no interference of overlapping ribs during lifting of the rearward ends of the bars. To this end, the vertical spacing of the ribs increases from the forward end or upper part of the bars to the rearward end or lower part thereof, corresponding to the greater vertical lifting movement of the rearward end relative to the forward end. (Figs. 5 and 6.)

The pins 84 and ribs 85 and 86 are provided for the purpose of distributing the air and cooling the grate bars, as more fully set forth in Patent No. 2,149,539, March 7, 1939, to D. J. Mossart, and Patent No. 2,062,481, December 1, 1936, to E. R. Stone, and both assigned to applicants' assignee. At the bottom of the bar are a plurality of the depending lugs 51 adapted to be received in the openings 52 in the upper surface of the cross-head 32, as previously explained.

Fig. 8 illustrates a modified grate bar made up of a pair of side members A and C, such as illustrated in Fig. 7.

Figs. 9 and 10 illustrate a third type of bar comprising a member B' identical with the central member B of Fig. 7, except that it is designed as a stationary grate bar rather than a reciprocatory bar and therefore has the downwardly-opening recess 59 in the lower face of its forward end for the reception of the upwardly-extending supporting and securing lug 58.

It will be seen that, by the provision of three standard grate bar members A, B and C, com-

posite or unitary grate bars of 3, 2 or 1 parts having corresponding widths, may be provided. The particular construction or width of grate bar to be used will depend largely upon the operating conditions of the furnace and stoker and the particular grade of fuel used.

While the construction herein illustrated shows the first row 26 of the extension grate construction made up of alternate reciprocatory and stationary grate bars, it will be apparent that the invention is not limited to this particular arrangement, but will cover any other arrangement wherein a number of reciprocatory bars are interspersed among a number of stationary bars.

It will be apparent from consideration of Figs. 3 and 4 that when the reciprocatory bars 28 are in their forwardmost or retracted position, the upper surfaces thereof are disposed below or forward of the corresponding surfaces of the stationary bars 29. Of course, when the reciprocatory bars are in their rearwardmost or projected position, their upper surfaces lie above and rearwardly of the corresponding surfaces of the stationary bars. This construction results in a positive agitating action by the bars upon the fuel bed passing thereover and assures that no clinker formations will form upon the bars.

While the invention has been shown in several forms, it will be obvious to those skilled in the art that it is not so limited, but is susceptible of various other changes and modifications without departing from the spirit thereof, and it is desired, therefore, that only such limitations shall be placed thereupon as are specifically set forth in the appended claims.

What we claim is:

1. In a progressive feed stoker, an extension grate structure disposed at the discharge end of said stoker, said structure comprising first and second transverse rows of grate bars, a cross-head extending transversely of the structure and serving to support the rearward ends of the grate bars of the first row and the forward ends of the grate bars of the second row, means for securing the bars of the second row to the cross-head, means securing alternate bars of the first row to the cross-head, and means through which there may be imparted to the cross-head straight-line reciprocatory movement longitudinally of the stoker whereby the bars of the second row and alternate bars of the first row will be reciprocated relative to the remaining bars of the first row.
2. Structure as specified in claim 1, including vertically-adjustable supporting means for the rearward ends of the grate bars of the second row.
3. In a progressive feed stoker, an extension grate structure disposed at the discharge end of said stoker, said structure comprising a transverse row of first grate bars, a transverse row of second grate bars, means securing a number of the first grate bars against movement longitudinally of the stoker, means for reciprocating the remaining first grate bars and the second grate bars longitudinally of the stoker, and means supporting the forward ends of the reciprocating first grate bars for substantially straight-line rolling movement.
4. Structure as specified in claim 3, including angularly-adjustable supporting means for the rearward ends of the second grate bars.
5. Structure as specified in claim 3, wherein the reciprocating movement imparted to grate bars lies in a substantially horizontal plane.
6. In a progressive feed stoker; an extension

grate structure disposed at the discharge end of underfeed section of said stoker, said structure comprising a cross-head arranged for reciprocating movement longitudinally of the stoker in an approximately horizontal plane; a transversely-extending row of first grate bars, said first bars extending downwardly and rearwardly from the discharge edge of underfeed section of the stoker to the cross-head; means connecting the rearward ends of alternate first bars to the cross-head; means supporting the forward ends of said alternate first bars for reciprocatory movement; means securing the forward ends of the remaining first bars against reciprocatory movement with the rearward ends of said remaining bars resting upon the cross-head, whereby reciprocation of the latter causes reciprocation of the alternate bars connected thereto; a transversely-extending row of second grate bars pivotally connected at their forward ends to the cross-head; and a vertically-adjustable structure for slidably supporting the rearward ends of said second bars.

7. Structure as specified in claim 6, wherein at the forward limit of movement of the reciprocating first grate bars the upper surfaces thereof are retracted below the corresponding surfaces of the remaining first grate bars, and at the rearward limit of movement of said reciprocating first grate bars the upper surfaces thereof are projected beyond the corresponding surfaces of the remaining first grate bars.

8. In a progressive feed stoker, an extension grate structure disposed at the discharge end of said stoker; said structure comprising a vertically-adjustable ash plate spaced rearwardly of the stoker; a cross-head adapted to be reciprocated in a direction longitudinally of the stoker disposed intermediate and spaced from the ash dump plate and the stoker; a plurality of parallel first grate bars disposed in side-by-side relation and bridging the space between the underfeed section and the cross-head, said plurality of first grate bars comprising alternate reciprocating and stationary bars having their rearward ends supported by the cross-head; fixed supporting means carried by the stoker for the forward ends of the stationary first bars; movable supporting means for the forward ends of the reciprocating first bars; means securing the rearward ends of said reciprocating first bars to the cross-head; and a plurality of reciprocating second grate bars disposed in side-by-side relation and bridging the space between the cross-head and the ash plate with their forward ends pivotally connected to said cross-head and their rearward ends slidably supported by said ash plate.

9. Structure as specified in claim 8, wherein the fixed supporting means for the forward ends of the stationary first bars comprises a plurality of upwardly-projecting lugs adapted to be received in corresponding shaped downwardly-opening notches in the lower faces of the forward ends of said stationary bars.

10. Structure as specified in claim 8, wherein the means for securing the rearward ends of the reciprocating first bars to the cross-head comprises a depending lug on the lower face of the rearward end of each of said bars adapted to be received in corresponding openings in the upper surface of the cross-head.

11. Structure as specified in claim 8, wherein the fixed supporting means for the forward ends of the stationary first bars comprises a plurality of upwardly-projecting lugs adapted to be re-

ceived in downwardly-opening mating notches in the lower faces of the forward ends of said stationary bars, and the means for securing the rearward ends of the reciprocating first bars to the cross-head comprises a plurality of depending lugs on the lower faces of the rearward ends of said reciprocating bars adapted to be received in mating openings in the upper surface of the cross-head.

12. In a progressive feed stoker, an extension grate construction disposed at the discharge end of said stoker; said structure including a transverse row of parallel grate bars disposed in side-by-side relation, said row comprising a number of reciprocating bars interspersed among a number of stationary bars; supporting means for the rearward ends of the grate bars and adapted to be reciprocated in a direction longitudinally of the stoker; supporting means for the forward ends of the grate bars and comprising a plurality of laterally-spaced upwardly-extending lugs adapted to be received in mating grooves in the lower faces of the forward ends of said stationary bars, said lugs having spaces therebetween corresponding to the widths of the interspersed reciprocating bars and adapted to normally receive the forward ends of the latter; and mating vertical lug and recess connections between the rearward ends of the reciprocating bars and their reciprocating supporting means, whereby the reciprocating bars may be removed from the extension grate construction by raising the former relative to the latter to separate the mating lugs and recesses.
13. In a progressive feed stoker having an extension grate construction disposed at the discharge end of said stoker; said construction including a transverse row of parallel grate bars disposed in side-by-side relation, said row comprising a number of reciprocating bars interspersed among a number of stationary bars; supporting means for the rearward ends of said reciprocating and stationary bars adapted to be reciprocated in a direction longitudinally of the stoker; supporting means for the forward ends of the reciprocating grate bars; supporting means for the forward ends of the stationary grate bars comprising a plurality of laterally-spaced upwardly-extending lugs adapted to mate with downwardly-opening grooves in the lower faces of the forward ends of said stationary bars, the spaces between adjacent lugs being at least as great as the width of the stationary bars supported by said lugs and being adapted to normally receive the forward ends of the interspersed reciprocating bars, removal of said last-mentioned bars providing for lateral sliding of the adjacent stationary bars off the lugs and into the spaces therebetween from whence they may be freely removed; and means connecting the rearward ends of the reciprocating bars to their reciprocating support, whereby reciprocation of the latter produces reciprocation of the former.
14. Structure as specified in claim 13, wherein the last-mentioned means comprises mating vertical lug and recess connections, whereby the reciprocating bars may be removed from the extension grate structure by raising the former relative to the latter to separate the mating lugs and recesses.
15. A progressive feed stoker having an extension grate construction disposed at the discharge end thereof, said construction comprising first and second transverse rows of parallel grate bars disposed in side-by-side relation, alternate bars

of the first row and all of the bars of the second row being mounted for movement bodily in the general direction of fuel feed for advancing and ejecting ash from the stoker; means for effecting such movement of the grate; a normally stationary member disposed transversely of the direction of fuel feed at the discharge end of the stoker and providing a support for the ash coming from the stoker, the forward end of the member extending beneath and forming a bearing support for the rear end of the extension grate; adjusting means for moving the ash-supporting member angularly about an axis extending transversely of the direction of fuel feed and disposed adjacent the forward end of the member whereby the rear portion of said member may be moved up or down.

16. Structure as specified in claim 15, wherein the surface of the ash-supporting member on which the rear end of the extension grate bars is supported lies in first and second planes defining an obtuse angle with the line of intersection of the planes extending transversely of the direction of fuel feed and the surfaces being so disposed that at one limit of angular adjustment

5 of the supporting member the rear end of the extension grate bears only on the surface lying in one of said planes, at the other limit of angular adjustment of the supporting member the grate bears only on the surface lying in the other of said planes, and at an intermediate point of adjustment of the supporting member the grate bears on the surface lying in one plane during a portion of its bodily movement and bears on the surface lying in the other plane during the remainder of the bodily movement.

10 15 20 25 17. Structure as specified in claim 15, including means supporting the forward ends of the bars of the second row in the extension grate construction for movement in an approximately horizontal plane at all times, and the rearward ends of said last-named bars being adapted to move in a plane varying from horizontal to an incline of several degrees, depending upon the angular adjustment of the ash-supporting member upon which they bear.

ROBERT A. FORESMAN.
